ATTORNEY

UNITED STATES PATENT OFFICE.

WILLIAM HENKE, OF ST. LOUIS, MISSOURI.

AUTOMOBILE-FENDER.

1,240,141.

Specification of Letters Patent. Patented Sept. 11, 1917.

Application filed June 27, 1917. Serial No. 177,355.

To all whom it may concern:

Be it known that I, WILLIAM HENKE, a citizen of the United States, residing at St. Louis, in the county of St. Louis City and State of Missouri, have invented new and useful Improvements in Automobile Fenders, of which the following is a specification.

My invention relates particularly to automobile fenders though not limited to that use alone and has for its objects; first to prevent serious injury to persons who might be run into by the vehicle to which the device is attached, and second, to provide a construction and arrangement of parts that while performing its operations in a very efficient manner the device does not interfere with the ordinary operation of the vehicle to which it is attached, and thirdly, to provide a fender which may be folded up when not in use, as when the machine is in the garage, whereby the fender will not be in the way.

With these and other objects in view which will readily appear as the nature of the invention is better understood the same consists in the improved construction and novel arrangement and combination of parts which will be hereinafter fully described and particularly pointed out in the claims.

I attain these objects by the mechanisms illustrated in the accompanying drawings, in which:—

Figure 1 is a top plan view of the preferred embodiment of my invention,

Fig. 2 is a side view of the mechanism illustrated in Fig. 1,

Fig. 3 is a horizontal vertical section taken through Fig. 1,

Fig. 4 is a partial side view of the mechanism in folded position,

Fig. 5 is a view in oblique perspective of the hinge connection of the device, the parts being separated slightly for a clearer disclosure,

Fig. 6 is a top plan view of the folding portion of the actuating bar of the device.

Like characters of reference indicate like parts in the various views.

In the drawings 1 designates the side frame members of the vehicle. Inasmuch as they are of usual construction and a detail description is not essential in the full and complete disclosure of my invention no further description is necessary.

I provide a U-shaped frame 2, the ends of which are attached to respective frame members 1. This frame 2 extends horizontally in front of the vehicle. Ears of hinges 3 are affixed to the transversely extending portion of frame 2. A member 4 is attached to each of the other ears of hinges 3 and overlies frame 2. A cross bar 5 extends across and is affixed to members 4 at their rear ends. A cross bar 6 extends across and is affixed to members 4 near their front ends leaving extensions of said members 4 projecting forward. The ends of these extensions of members 4 are split longitudinally and the outer members 7 of the split ends 70 of the same are bent around pintles 8 which extend transversely and have ends projecting inwardly from said ends 7. Hinged members 9 are pivotally connected to the members 4. The ends of pintles 8 are upset to prevent them from working out of engagement with members 4 and 9. The inner members 11 of the split ends of extensions 4 are bent downwardly around the inner members 10 of the split ends of members 9 and engage the under surface of members 9 some distance beyond the axis of the hinge and prevent the members 9 from swinging downwardly from their normal position respecting members 4. The outer members 12 of the split ends of members 9 are bent upwardly to engage the upper surface of members 4 when the fender is folded up whereby the fender is held in its folded-up position, see Fig. 4. A cross bar 13 is affixed to the outer ends of hinge members 9 and projects beyond the hinge member on either side. On the outer ends of cross bar 13 members 14 are affixed one on each end and extend forward therefrom. A cross bar 15 connects the outer ends of members 14. Thus members 4, 5, 6, 9, 13, 14 and 15 form a tilting fender frame hinged to the stationary frame 2 by the hinges 3; the rear end of said tilting fender frame overlying said stationary frame 2.

It will be noted that members 13, 14 and 15 form an opening within them. A wire netting 16 is extended across this opening and secured to the inner edges of members 13, 14 and 15 by means of strips 17 which are riveted to said members the netting having first been placed between the netting 16 being preferably bagged. Runners 18 are affixed to the outer ends of members 14 and 110

contact the road-way when the fender frame is tilted down in working position.

A cross plate 19 is provided which extends across frame 2 and is affixed thereto just forward of the overlying cross bar 5 of the tilting fender frame. A recess is formed at about the middle of cross plate 19, ears 20 extending downwardly from the sides thereof. A pin 21 is horizontally disposed across the space between the said ears 20, the ends of which are affixed to said ears 20. A slot 22 is formed in cross bar 5 of the tilting fender frame in line with said recess. A catch member 24 is pivoted on said pin 21 at a point intermediate the ends thereof and has a hook shaped catch 24' formed at its upper end, the bill of said catch lying to the rear of the main portion of the catch member and adapted to enter the slot 22 from the upper side thereof to engage the upper side of cross bar 5 in front of said slot to hold the fender frame in its normal horizontal position. The hook shaped catch member 24' is shaped so that it will disengage readily from the cross bar 5 when said catch member 24 is swung on the pin 21 to move the hook shaped catch out of the path of said cross bar. An actuating bar 23 extends underneath the fender structure and has its rear end pivotally secured to the lower end of said catch member, as designated at 23'. When the fender frame is in its horizontal position as above described the tendency of said frame to assume its forward position is prevented by the catch 24' engaging the upper surface of bar 5. The actuating bar 23 is hinged at a point in front of the pivotal connection formed between the members 4 and hinged members 9 in the following manner. The bar 23 is composed of two members, the adjacent ends thereof being split longitudinally. The left member 25 of the split end of the rear member of the actuating bar 23 is bent around a pintle 26 disposed transversely of said bar. The right member 27 of the split end of the forward end of actuating bar 23 is bent around the projecting end of said pintle. The ends of said pintle are upset thereby preventing said pintle from working out of engagement with the ends 25 and 27. The right member 28 of the split end of the rear member of said actuating bar is bent downwardly around the hinge and engages the under surface of the upwardly extending member of said actuating bar to prevent said forward end from swinging outwardly from its normal position respecting the rear member of said actuating bar and latch 29 is pivotally mounted upon the upper surface of the forward members of said actuating bar and engages the projection 30 mounted on said rear member of said actuating bar whereby the forward member of said actuating bar is prevented from swinging up-

wardly respecting the rear members thereof. A spring 31 serves to hold the latch and projection in engagement.

When it is desired to hold the fender up the latch 29 is disengaged from the projection 30 by swinging it upon its pivot. The front of the tilting frame is then swung upon the pintles 8 until the ends 12 and hinge members 9 engage the upper surface of members 4. Said ends 12 are so disposed that when they engage the upper surface of members 4 the forward end of the fender frame is disposed at a point in back of its vertical center whereby the gravitational tendency thereof keeps it in its folded position with the members 12 engaging the upper surface members 4. See Fig. 4. A hole 32 is formed in the netting 16 for convenient manipulation of the latch 29. A stop 29' is formed on the lower end of catch member 24 to prevent said catch member and the rear end of said actuating bar swinging past their centers.

Said actuating bar 23 extends forward under the tilting fender frame and pivotally engages a contact rod 33 which extends across in front of said tilting fender frame. The ends of said contact rod 33 are bent to form arms 34 which terminate in pivot pins journaled at 35 on the said members 14 near the outer end thereof. A runner 33' is provided on the front end of actuating bar 23 to contact the ground when the fender is in its operative position.

In the operation of the device the tilting fender frame is held in its horizontal inoperative position as hereinbefore described. When the contact rod 33 by reason of its exposed position contacts any object by the forward movement of the vehicle it rocks backward relative to the vehicle and pushes the actuating bar 23 backward which releases catch 24' from engagement with cross bar 5, thus allowing the tilting fender frame to tilt down until runners 18 contact the road-way and slide along the same.

To reset the tilting fender frame in its normal inoperative position the outer end of the frame is manually lifted. The catch 24' is then moved into the path of the cross bar 5 to engage the tilting fender frame as hereinbefore described. The gravitating tendency of the tilting frame serves to hold said catch 24' in engagement with cross bar 5, thus preventing accidental dropping of the tilting fender frame.

Having thus described my invention, what I claim is:

1. A fender comprising a stationary frame, a gravity operating tilting frame, a hinged connection between said frames, a catch mounted upon said stationary frame in working relation with said tilting frame, an actuating bar in operable connection with said catch extending in front of afore-

- said frames, a contact rod pivotally attached to said actuating bar, arms affixed to said contact rod, and pivotal supports for said arms mounted upon said tilting frame.
2. A fender comprising a stationary frame, a gravity operated tiltable fender frame overlying said stationary frame, a pivotal connection between said frames, a catch mounted on the stationary frame in working relation to said overlying tiltable frame, an actuating bar in operative connection with said catch extending to a point in front of said tiltable frame, a contact rod pivotally connected to the outwardly extending end of said bar, and arms engaging said cross bar, a pivotal support for said arms mounted upon said tiltable fender frame.
3. A fender comprising a stationary frame, a gravity operated tiltable fender frame overlying said stationary frame, a pivotal connection between said frame engaging said fender frame near its center, a catch mounted upon said stationary frame in working relation with the said overlying tiltable frame, an actuating bar in working relation with said catch extending underneath said tiltable fender frame to a point in front of said frame, a contact rod engaging the outer end of said actuating bar, and arms engaging said contact rod, said arms being pivotally mounted upon said tilting frame.
4. A fender comprising a stationary frame, a gravity operated tilting frame overlying the stationary frame, a pivotal connection between said frames, a catch mounted on the stationary frame in working relation to said tiltable frame, an actuating bar operatively associated with said catch and extending beneath said tiltable frame to a point in advance of the latter, a contact rod carried by said actuating bar, and said actuating bar including hinged
- connected sections, with the hinge disposed in proximity to the hinged connection between the respective sections of the fender, whereby said tiltable section and a section of said actuating bar are susceptible of assuming an upright folded position.
5. A fender comprising a stationary frame, a gravity operated tilting frame overlying said stationary frame, a pivotal connection between said frames, a catch mounted on said stationary frame in working relation to said tiltable frame, an actuating bar operatively associated with said catch and extending beyond the forward end of said fender, a contact rod operatively associated with said bar and tilting frame, said actuating bar comprising hingedly connected sections to permit the tiltable frame to assume an upright folded position, and a spring pressed manually operable latch element bridging the joint between the respective sections of said actuating rod for holding the latter in operative position.
6. A fender comprising a stationary frame, a gravity operated tiltable fender frame overlying the stationary frame, a pivotal connection between said frames, foraminated material secured to the tiltable frame, a catch mounted on said stationary frame in working relation with the tiltable frame, an actuating bar operatively associated with said catch and extending beneath said foraminated material to a point in advance of said tiltable frame, a contact rod pivotally connected with said bar and said tiltable frame, said actuating bar comprising hingedly connected sections, a manually operable latch element bridging the joint between said sections for holding said sections normally fixed relatively, and said foraminated material having a hand receiving opening immediately above said latch element.

In testimony whereof I affix my signature.
WILLIAM HENKE.
